STEAM DRIER SYSTEM

Alfred G. Kernin, Mosinee, Wis., assignor to
 Mosinee Paper Mills Company, Mosinee, Wis.,
 a corporation of Wisconsin

Application August 24, 1936, Serial No. 97,617

2 Claims. (Cl. 34—48)

This invention relates to a steam drier system, and more particularly to a steam drum drier system for paper machines and the like.

In paper machine driers heretofore it has been customary to employ steam traps or the like in the condensate drainage lines from the steam drier drums. In some instances the steam drier drums are divided into sections and the condensate together with steam discharged from one section into a steam separator, from which the steam is led into a second section of driers and the condensate from the second drier section discharged into another separator. From this last separator, the steam may be fed to only a small number or one drier and the condensate therefrom exhausted into a vacuum pump or drained into a condensate tank.

According to my observations, steam traps frequently result in the circulation of steam being too sluggish for maximum efficiency of heat transfer from the drier drum shells to the paper being dried. Furthermore, in order to keep the machine operating at relatively efficient drying rates, continuous inspection of the system and replacement of parts are required. Often condensate from one section of driers is forced into another drier section owing to the difference in pressure at which the various sections are operated, and this results in curtailed production owing to lack of proper drainage and inefficient heat transfer.

In accordance with the present invention, the condensate drainage lines are provided with members having fixed orifices, which have a maximum capacity for the drainage of condensate but which allow a minimum passage of steam therethrough. When the drier system is in operation, the flow of condensate and excess steam is controlled solely by means of fixed orifices. The excess steam and flashed steam from the condensate in the first section is then condensed in a drier or driers near the wet end or dry end, as preferred.

The drainage system of my invention comprises no movable parts, except a check valve in the line from the expansion chamber, or steam and water separator, to the condensate tank. Other valves are provided in the individual steam and condensate lines to and from the drier drums but only for the purpose of closing down the system, or some part of it, and not for controlling the rate of flow of condensate during normal operation of the drier system.

It is therefore an important object of this invention to provide a steam drier system for paper

making machines and the like wherein the rate of flow of condensate and excess steam from the drier drums is automatically controlled by members having fixed orifices and wherein the number of movable parts for the control of the system is reduced to a minimum.

A further important object of this invention is to provide a steam drier system having fixed orifices positioned in the condensate drainage conduits to give a maximum capacity for flow of condensate with a minimum passage of steam into the drainage system.

Other and further important objects of this invention will be apparent from the disclosures in the specification and the accompanying drawings.

This invention (in a preferred form) is illustrated in the drawings and hereinafter more fully described.

On the drawings:

Figure 1 is a broken, somewhat diagrammatic side elevational view of a steam drier system for a paper making machine or the like, embodying the principles of my invention.

Figure 2 is an enlarged fragmentary view, partly in section, of a valved fitting having an orificed member for controlling the condensate drainage from a drier drum.

As shown on the drawings:

The reference numerals 10 indicate a plurality of steam drier drums forming a part of the drying system of a paper machine or the like. It is customary to arrange the paper drier drums 10 in two horizontal tiers, with successive drums in staggered relation, so that the paper to be dried (not shown) passes successively around lower and upper drums in a zigzag path through the drier section. It will be understood, however, that my invention is applicable to other arrangements of drier drums and to drier systems other than paper making machine drying systems, as in the drying of fabrics and the like.

As shown in Fig. 1, a number of felt driers 11 are positioned above the upper tier of paper drier drums but form a part of the same drying system. Steam is supplied through a pipe 12 to a steam header 13 and thence by means of individual pipes 14 to the paper driers 10 with the exception of the first drier drum 25, located at the wet end. The felt driers 11 may be supplied with steam by individual pipelines leading from the header 13, as the pipelines 15, or, as in some instances, by a branch pipeline 16 from one of the paper drier pipelines 14a. Each of the steam pipes 14, 14a, 15 and 16 is provided with a valve 17 which is normally allowed to remain fully open

when the drying system is in operation, but which is fully closed when the system is shut down, or when the drier controlled by such valve is desired to be shut off.

- 5 A condensate drainage line 18 extends from each of the paper driers 10 to a condensate return header 19. Similar condensate drainage lines 20 connect the felt driers 11 with said condensate header 19. In each of said condensate drainage lines 18 and 20 is positioned a fitting, designated by the reference letter A, which will later be described.

The condensate header 19 leads to an expansion chamber 21 for receiving the condensate and any steam that may pass into said header 19. Said header 19 connects into the expansion chamber 21 near the top thereof, as at 22. A discharge condensate pipeline 23 is connected near the bottom of said expansion chamber 21, as at 24, to return the condensate to the boiler feed line or to other desired points. The discharge pipeline 23 is arranged to discharge at a height sufficient to give the desired pressure in the expansion chamber.

- 25 One or more of the paper driers at the wet end of the drier section, in accordance with my invention, is connected up somewhat differently from that described for the remaining driers. The first drier 25, for instance, is connected by a 30 pipeline 26 to the upper end of the expansion chamber to receive flash steam from said chamber. The condensate from said first drier 25 is not led into the condensate header 19 but is discharged through a separate condensate pipeline 27 to a hot well or vacuum pump.

The fitting A will now be described. As best shown in Fig. 2, said fitting A comprises a generally T-shaped body portion 33, one leg of which is provided with a threaded end 34 for receiving 40 a condensate drainage pipeline 18 or 20. Another leg of said body portion 33 is provided with a threaded end 35 for receiving a short length of pipe 36 that is connected into the condensate header 19. Said fitting A is provided with a third 45 threaded outlet 37 which is controlled by a valve 38 and from which samples of condensate may be drawn to determine the rate of discharge of condensate.

A valve 39 is interposed between the pipe 18 50 and the body of the fitting A, and a valve 40 is interposed between the pipe 36 and the body of the fitting A. Normally these valves are fully 55 opened but are intended to be closed when the drier is shut down. The valve 40 may also be closed when it is desired to withdraw condensate through the outlet 37.

An orificed plug 41 is adapted to be threaded into an opening 42 in the body portion of the fitting A just beyond the valve 39 and between 60 said valve 39 and each of the other valves 38 and 40. Said plug 41 is provided with a fixed orifice 43 of such dimensions as to take care of the maximum flow of condensate when the drying system is being operated under a predetermined 65 set of conditions as to temperatures, pressures, speed of travel of the paper, etc. In order to provide for the replacement of the orificed plug 41, the wall portion of the fitting opposite said plug 41 is provided with an opening 44 of 70 larger diameter than the opening 42 and having a removable plug 45 threaded thereinto.

When the drying system is operating, steam is supplied from the supply pipe 12 into the steam header 13 and from said header through the individual pipes 14 into the paper drier drums 10.

The pipelines 15 and 16 also conduct steam into the felt driers 11. The condensate from said driers 10 and 11 is removed from said drums through the condensate lines 18 and 20, respectively, for drainage into the condensate header 19. From the header 19, the condensate passes into the top of the expansion chamber 21, where some of the condensate is flashed into steam and where any steam carried along with the condensate is separated therefrom, the condensate going to the bottom of said expansion chamber 21 and being exhausted therefrom through the pipe 23.

The steam thus separated from the condensate in the expansion chamber 21 passes under its own reduced pressure head through the pipe 26 15 into the first drier drum 25, or there may be more than one such drum. Ordinarily the volume of the steam that is separated from the condensate in the expansion chamber 21 will be sufficient to heat only one, or possibly two or 20 three, drier drums. The condensate from the drier drum 25 is drained into a separate condensate pipeline 27, and then to hot well or vacuum pump.

Only a minimum amount of steam passes 25 through the orifices 43 into the condensate header 19. From the expansion chamber 21, the condensate is drawn through a pipeline 23, in which is positioned a check valve 50 to prevent any back-flow of condensate from the condensate tank 30 (not shown) into the expansion chamber.

By closing the valve 40 and leaving the valves 39 and 38 opened, it is possible to measure the work done by each drier drum 10 by allowing the condensate to pass through the outlet 37 into a 35 measuring vessel, or by weighing the condensate. The measuring vessel may be graduated in gallons or pounds so that the quantities of condensate removed from the dried drums can be determined per unit of time. This is a very desirable 40 feature since each drier drum can be separately tested and if it is not performing up to standard, steps can be taken to bring it back to its maximum operating capacity.

By the use of my system, it is very simple to 45 arrange the driers to operate at any predetermined temperature by placing the proper sized orifices in the condensate lines from the drier drums. The provision of the plugs 41 permits 50 the orificed plugs 41 to be readily replaced or exchanged for plugs having different sizes of orifices.

As contrasted with the drying systems heretofore used, my system has only one movable part when in operation. Since the valves, with 55 the exception of the steam supply regulating valve 51, are all normally in fully opened or closed position when the system is in operation, practically no supervision of the valves in the system is required. The check valve 50, of course, operates automatically, leaving only the regulating valve 51 in the steam supply line for adjustment by the operator during the operation of the drying system. It will be understood that in some 60 drying installations there may be driers for the bottom drier felts and in that case, the bottom felt driers may be supplied directly with steam from the supply line 12 through a separate regulating valve, or the main regulating valve supplying steam to the regular paper driers. 65

I am aware that many changes may be made and numerous details of construction may be varied through a wide range without departing from the principles of this invention, and I, therefore, do not purpose limiting the patent granted 70 75

hereon otherwise than necessitated by the prior art.

I claim as my invention:

- 5 1. In a steam drier system having a plurality of steam driers, means for supplying steam thereto and conduits for the removal of condensate and steam therefrom, a branched structure in each of said conduits having an orificed member in said structure having an orifice of reduced dimensions for controlling the flow of condensate and steam therethrough, a valve ahead of and a valve beyond said orifice in branches of said structure and a removable closure member in said structure opposite said orificed member to facili-

tate the removal and insertion of such orificed member.

2. In a steam drier system having a plurality of steam driers, means for supplying steam thereto and conduits for the removal of condensate and steam therefrom, a branched fitting in each of said conduits having an orificed member for controlling the passage of condensate and steam therethrough, a valve in said fitting ahead of said orifice, a valve in each of two branches of said fitting beyond said orifice and a removable plug in said fitting opposite said orificed member to facilitate its removal. 5 10

ALFRED G. KERNIN.
